Atty

UNITED STATES PATENT OFFICE.

IRA A. WEAVER, OF SPRINGFIELD, ILLINOIS.

PISTON.

Application filed June 9, 1927. Serial No. 197,628.

My invention concerns betterments in internal-combustion engines, whereby to improve the lubrication thereof, one aim of the invention being to so construct the pistons 5 of the engine that the excess oil tending to pass upwardly by their piston-rings will be automatically discharged back into the crank-case before it has an opportunity to cause harmful effects, such as the fouling of 10 the spark plugs, etc.

A further purpose of the invention is to maintain the crank-case at a very slight pressure above atmospheric to prevent the entrance of any substantial amount of road dust 15 into it through the breather-tube, thereby keeping the supply of lubricating oil in better condition for effective use.

To enable those skilled in this art to have a full and complete understanding of the invention, in the accompanying drawing forming 20 a part of this specification, I have illustrated a present desirable embodiment of the invention, the same reference characters being used in the several views for like parts.

25 In this drawing:

Figure 1 is a central vertical section through the piston;

Figure 2 is a horizontal section on line 2—2 of Figure 1 and

30 Figure 3 is a section through one of the piston-rings, on line 3—3 of Figure 2.

By reference to the drawing, it will be observed that the upper portion or head part 11 of the piston 12 has three piston-ring 35 grooves 13, 14 and 15 accommodating the corresponding number of piston-rings 16, 17 and 18 of special construction and forming, in connection with the floating blocks or guide shoes 19 rockingly mounted on opposite sides of the lower portion of the piston, the subject-matter of my copending patent 40 application Serial No. 224,805, filed October 8th, 1927.

Each such piston-ring externally snugly 45 fits the interior of the engine cylinder 21 and internally it has a plurality of spaced lugs or projections 22, 22 bearing against the inner circular wall of the groove in which the ring is located, such protuberances being rounded off at the top and bottom at 23, 24, (Figure 50 3) to maintain communication between the arcuate spaces between the ring and the inner piston-ring groove wall on opposite sides of the projections.

55 The top wall of the upper piston-ring groove has a hole 25 extended through it in

register and communication with the circular chamber back of the associated piston-ring 16; the wall between the grooves 13 and 14 is similarly apertured at 26 diametrically opposite the port 25; the wall between the grooves 14 and 15 is likewise ported at 27 below the aperture 25; and the bottom wall of the lower groove 15 has a passage 28 therethrough below the hole 26, such port 28 having its lower end equipped with a leaf-spring valve 29, the inner end of which is riveted or otherwise fixedly fastened to the piston in any approved manner to permit the valve to open and close by flexure of the spring. 60 65 70

Obviously, during the intake stroke of the piston, valve 29 will be closed and there will be no interference with the gaseous explosive mixture drawn into the firing chamber above the piston. 75

During the compression and power or explosion strokes of the piston, a very small part of the gases under pressure enter the port 25 and traverse the tortuous divided passage around both sides of the piston behind 80 the piston-rings forcing the contents thereof out of the discharge-port 28 into the engine crank-case, the valve 29 opening automatically under the pressure exerted on its top face. 85

Thus any excess lubricating oil and any 90 contaminating or diluting ingredients, such as raw gasoline, etc., in such circuitous conduit are blown out and are thereby prevented from passing upwardly into the combustion chamber where, in the form of carbon, they 95 would foul the spark-plugs and valves.

In this connection, it is well to bear in mind that such excess oil tends to travel upwardly into the firing chamber through the spaces behind the piston-rings, and it is from 95 such compartments that it is forced outwardly downwardly.

With a construction of this kind adequate lubrication may be applied to the cylinder and piston without danger of pumping the 100 oil past the piston-rings into the combustion chamber, because the excess is automatically eliminated or removed in the manner specified.

Inasmuch as there is more or less constant 105 ly a delivery of gases under pressure through the piston into the engine crank-case, there is of necessity a constant flow out through the breather-tube (not shown) carrying with it any gases and water vapors, whereby dilution of the oil supply in the crank-case 110 will be reduced to a minimum and the en-

trance of road dust is prevented, thus precluding its mingling with the lubricating oil to the detriment of the friction-reducing properties of the latter.

- 5 Dilution of the lubricating oil tends to occur in greatest degree when the engine is first started and it is to be observed that my novel means for the prevention thereof becomes operative the moment the engine 10 starts.

Those skilled in this art will readily understand that the invention is susceptible of a variety of embodiments and that the one presented is merely by way of example only, 15 the scope of the invention being defined by the appended claims.

I claim:

1. A piston for internal-combustion engines having a piston-ring groove and a piston-ring therein and means to cause a portion of the gases under pressure above the piston to pass through the space afforded by the piston ring-groove back of the piston-ring to blow out its contents.
- 25 2. A piston for internal-combustion engines having a plurality of piston-ring grooves and piston-rings therein and means to cause a portion of the gases under pressure above the piston to pass in series through the spaces afforded by the piston-ring grooves back of their piston-rings to blow out their contents.
- 30 3. A piston for internal-combustion en-

gines having a piston-ring groove and a piston-ring therein and means to cause a portion of the gases under pressure above the piston to enter the space afforded by said groove back of its piston-ring at one point and to leave such space at a point remote therefrom whereby to blow out the contents 40 of such space.

4. A piston for internal-combustion engines having a piston-ring groove and a piston-ring therein and means to cause a portion of the gases under pressure above the piston 45 to enter the space afforded by said groove back of its piston-ring at one point and to leave such space at a point remote therefrom whereby to blow out the contents of such space, in combination with valve means to close said passage during the intake-stroke of the piston.

5. A piston for internal-combustion engines having a plurality of piston-ring grooves, piston-rings therein and means to cause a portion of the gases under pressure above the piston to pass in series through the spaces afforded by the piston-ring grooves back of their piston-rings to blow out their contents, in combination with valve means 55 to close such conduit during the intake stroke of the piston.

In witness whereof I have hereunto set my hand.

IRA A. WEAVER.
